UNITED STATES PATENT OFFICE.

RALPH H. UPSON, OF AKRON, OHIO, ASSIGNOR TO THE GOODYEAR TIRE & RUBBER COMPANY, OF AKRON, OHIO, A CORPORATION OF OHIO.

KITE-BALLOON.

1,341,248.

Specification of Letters Patent.

Patented May 25, 1920.

Application filed November 9, 1916. Serial No. 130,381.

To all whom it may concern:

Be it known that I, RALPH H. UPSON, a citizen of the United States, residing at Akron, in the county of Summit and State 5 of Ohio, have invented new and useful Improvements in Kite-Balloons, of which the following is a specification.

My present invention has a generic reference to kite balloons of the general type disclosed by me in my application No. 104,691, 10 filed June 20, 1916, but in particular contemplates improvements in balloons of this class and in balloons in general which will render them more stable in use; which will 15 give them a greater lifting power for the attainment of increased heights; and which will offer a most satisfactory solution of the suspension problem.

One of the principal objects of the invention 20 has been to centralize the load-supporting elements of a balloon, whether captive or dirigible, in such manner that the slung weight which the balloon is designed to lift may be suspended by means arranged in the 25 vertical plane of suspension within the balloon interior.

It has been another of the principal objects of this invention to provide a double 30 gas envelop for the balloon, the general shape of the craft appearing to be that of a pair of separate balloons mated in sidewise fashion. The gas compartment of each envelop is separated from that of the other and is provided with its own ballonet, the 35 tail cup, or cups, being rearwardly attached conjointly between both balloon portions. The pilot's basket is slung below the composite balloon in a manner providing a centralized suspension symmetrically distributed 40 between both balloon surfaces.

Aside from the increased lift which is secured by an enlargement of the cubical contents of the gas compartments owing to the employment of two mated balloon bodies, it 45 is an object of the invention to secure an increased lift from the wind action upon the composite envelop of my new type balloon. To render this kite action more efficient, I make the under surfaces of my mated envelop sections of straight line instead of a curved conformation, so far as the longitudinal elements of the sections are concerned. 50

It has also been the object of this inven-

tion to so place the various side and rudder fins as to provide for a symmetrical distribution of the wind pressures, each of the 55 separate bodies of the composite balloon bearing its own rudder fins in conjunction with its independent ballonet, while one side fin is supported upon the exterior surface of each balloon body to form a group 60 tending to eliminate both yawing and pitching of the craft.

The above and additional objects of a similar nature, which will be hereinafter 65 more specifically treated, may be accomplished by such means as are illustrated in the accompanying drawings, described in the following specification, and then more particularly pointed out in the claims which 70 are appended hereto and form a part of this application.

With reference to the drawings, wherein there has been illustrated a preferred embodiment of the invention as it is reduced 75 to practice, and throughout the several views of which, similar reference numbers designate corresponding parts:

Figure 1 is a side elevation of my composite balloon; and

Fig. 2 is a plan view; and
Fig. 3 is a cross-sectional view taken on a plane indicated by the line 3—3 of Fig. 1.

With the exception of shape, the methods of suspending the pilot's car, the construction of and the method of attaching the tail appendage, and arrangement of the side fins, each of the balloon bodies which are mated to form a composite craft by this invention, corresponds to the kite balloon 90 structure disclosed in my application referred to above.

In the drawings, the two balloon bodies are designated by the numerals 10 and 11 and are each equipped with a gas valve 12 automatically controllable through the medium of an operated cord 12' by the ballonet 13, which latter is arranged within the tail portion of the gas envelop which carries a dependent inlet funnel 14. The funnel mouth 100 15 of each of these funnels is directed forwardly in order that the ballonet may be filled by the wind current, and each balloon body is equipped with a pair of rudder fins 16 secured on the under surface thereof and 105 encompassing the funnel 14. Each of the

balloon portions has its independent filling neck 17 through which extends the cord 18 controlling the rip panel 19, while the operator of the composite balloon may also control the gas valve 12 independently of the ballonet's action through the medium of the cord 20, which is led to the pilot's car or basket 21 through its individual appendix 22.

10 The elevational shape of the balloon bodies (Fig. 1) is to be differentiated from the symmetrical stream line form which I disclosed in my mentioned prior application, since I have flattened the bottom and given 15 the top an increased arch by the insertion of triangular ring gores 23 whose widest portion is placed along the upper side of the balloon and tapers on each side therefrom to a single seam at the lower edge. If desired, I may accomplish the same object by 20 cutting triangular gores of the same size from successive sections of the balloon but with the widest portions of the gores at the bottom surface. By use of the first method 25 I gain an elongated balloon while the second method shortens the balloon longitudinally, although the resultant shape is approximately the same in both cases. The effect of 30 this alteration in the balloon shape is to establish an approximation, in side elevation, of an aeroplane section, the upper surface providing the camber.

The two balloon bodies are separated by a vertical partition 24 which forms the central point for the suspension of the pilot's basket, additional suspension lines depending from the exterior surface of each balloon body in the customary fashion. By this means, the slung weight is symmetrically 40 distributed over the whole portion of the lifting device.

A single tail cup 25 has been found sufficient to head the composite balloon into the wind and to maintain it steadily in that 45 position. The appendage 25 does not partake of the usual tail cup shape, being merely a linear flap which presents a concave portion to the wind and has suspension lines 26 cross-connecting from each flap 50 corner to each ballonet funnel 14 of the composite balloon body, while lift lines 26' connect the two upper corners of the flap 25 directly to the tail of the corresponding balloon.

55 The side fins are designated by the numerals 27 and are apportioned one to each balloon, being arranged over the exterior suspension lines 28. The latter are arranged upon each side of the main suspension lines 60 which are preferably attached to and disposed in the plane of the central partition 24. A towing cable 29 is in the form of a yoke which connects to the opposite suspension lines 28 at the forward portion of each 65 balloon body, while the usual maneuvering

ropes 30 are dependent from both of the balloon portions 10 and 11, to permit control of the balloon when near the ground.

It will be seen from the foregoing that the improvements comprehended by my present invention come under three main headings. The first is concerned with the suspension of the pilot's basket, the load which the balloon is designed to lift, from the middle of the whole envelop, the load- 75 supporting means being alined in the same vertical plane with the slung weight. The second has relation to the formation of a composite balloon by a sidewise joining of relatively independent balloon bodies, each 80 of which is provided with its separate gas compartment, ballonet and rudder or keel fins 16, while the composite balloon as a whole provides for the common and inter-related support of the tail appendage, and 85 other appurtenances. The third main improvement has reference to the shaping of each balloon body by means of the triangular inserts or gores to provide substantially the elevational appearance of an aero- 90 plane section.

The combined effect of all of these improvements is to render my kite balloon more stable in its flying attitude and to provide it with enhanced lifting powers which 95 render it particularly adaptable for long distance military observation.

It will be understood that the term "composite" balloon envelop, as used in the appended claims, signifies the supporting gas 100 bag or envelop, which is constructed from a number of relatively independent separate units, which are correlated in the construction to act, as far as the carrying of the load is concerned, as a unit.

105 What I claim is:

1. In a balloon, a plurality of separate balloon bodies longitudinally mated to form a composite gas containing envelop, an air ballonet associated with each balloon body, each ballonet being constructed for automatic inflation and deflation in response to variations in the gas pressure within its respective balloon body, and a load sustaining fuselage arranged to suspend the load from the longitudinal center of the balloon and having auxiliary connections with each separate balloon body.

115 2. In a balloon, a pair of separate balloon bodies longitudinally mated to form a composite balloon envelop; a separate ballonet for each balloon body; a separate filling neck for each balloon body; and a basket and tail cup conjointly supported by and between said balloon bodies.

120 3. In a balloon, a pair of separate balloon bodies longitudinally mated to form a composite balloon envelop; a partition separating the balloon bodies of the composite envelop; and means for suspending the 130

weight to be supported by the balloon from said partition and equally from opposite sides of the respective balloon bodies.

4. In a balloon, separate balloon bodies

5 longitudinally mated to provide a composite balloon envelop; keel fins independently supported by the respective balloon bodies; side fins independently supported by the balloon bodies to form a stabilizing 10 group for the composite balloon as a whole, and a tail fin conjointly supported by the separate balloon bodies.

5. In a balloon, a gas envelop having incorporated in its structure a series of triangular gores spaced at intervals along its 15 length, to give in side elevation, a configuration corresponding to the side elevational contour of an aeroplane supporting surface.

6. In a balloon, a gas containing envelop 20 comprising a plurality of longitudinally mated balloon bodies each of which is patterned to present in side elevation a substantially straight lower outline and an arched upper outline, a longitudinal partition 25 defining the juncture between the separate balloon bodies, and a fuselage constructed to suspend a load from the partition and having auxiliary connections with each separate balloon body.

30 7. In a balloon, a pair of separate balloon bodies, each constructed to present, in side elevation, a configuration corresponding to the side elevational contour of an aeroplane supporting surface, and a partition 35 centrally uniting said balloon bodies to form a composite gas envelop.

8. In a balloon, a pair of envelops mated longitudinally to form a composite gas bag, a load to be swung below the gas bag, a longitudinal 40 partition erected within the gas bag and defining the junction of the separate envelops, said partition being located

centrally in the plane of suspension for the said load, and means of suspending said load mainly from said partition.

45

9. In a balloon, a plurality of separate balloon bodies longitudinally mated to form a composite balloon envelop, a central longitudinal wall defining the junction of the balloon bodies, a separate balloonnet for each 50 balloon body, a separate filling neck for each balloon body, and a basket conjointly supported by and between said bodies and partially sustained by the said wall.

10. In a kite balloon, separate balloon 55 bodies longitudinally mated to form a composite balloon envelop; keel fins independently supported by the respective balloon bodies, and side fins independently supported by the balloon bodies to form with the 60 keel fins a stabilizing group for the composite balloon as a whole.

11. In a balloon, a gas containing envelop comprising a plurality of longitudinally mated balloon bodies, each having incorporated therein a plurality of triangular gores spaced at intervals to give in side elevation a configuration corresponding to the side elevational contour of an aeroplane supporting structure, an air balloonnet associated with each balloon body and constructed for automatic inflation and deflation in response to variations in the gas pressure with its respective envelop, and means for suspending a load from the longitudinal 70 center of the envelop.

65

In testimony whereof I have signed my name in the presence of two subscribing witnesses.
